EX

2830

United States Patent Office.

WISNER H. TOWNSEND, OF NEW YORK, N. Y.

Design No. 2,830, dated November 5, 1867.

DESIGN FOR OIL-CLOTHS.

The Schedule referred to in these Letters Patent and making part of the same.

TO ALL WHOM IT MAY CONCERN:

Be it known that I, WISNER H. TOWNSEND, of the city, county, and State of New York, have originated and designed a new Pattern for Oil-Cloths, of which the following is a full, clear, and exact description, reference being had to the accompanying drawing, making part of this specification.

This invention relates to a new and original design for oil-cloths, the same being a representation of inlaid marble blocks of different colors or tints.

The accompanying drawing represents my design, which is composed of squares adjoining each other, and bounded or separated by narrow strips, *a*, which are a representation of veined white marble. These squares are subdivided by strips, *b*, which are also a representation of veined white marble. The strips *b* extend one from each angle of each square inward to a centre-piece, *c*, which has eight sides, four of which are much wider than the other four, there being an alternate wide and narrow side. These centre-pieces represent a dark-veined marble, and adjoining the wide sides of the centre-pieces there are blocks, *d*, which fill up the space or enclosure within the strips *a b*, the blocks *d* representing a blue-veined marble.

What I claim as my invention, and desire to secure by Letters Patent, is—

The design for oil-cloths, as herein shown and described.

The above specification of my invention signed by me this 24th day of September, 1867.

WISNER H. TOWNSEND.
